UNITED STATES PATENT OFFICE.

GEORGE F. HUTCHINS, OF WORCESTER, MASSACHUSETTS, ASSIGNOR TO
THE KNOWLES' LOOM WORKS, OF SAME PLACE.

VARIABLE TAKE-UP MOTION FOR LOOMS.

SPECIFICATION forming part of Letters Patent No. 340,216, dated April 20, 1886.

Application filed July 30, 1885. Serial No. 173,078. (No model.)

To all whom it may concern:

Be it known that I, GEORGE F. HUTCHINS, a citizen of the United States, residing at Worcester, in the county of Worcester and State of Massachusetts, have invented certain new and useful Improvements in Variable Take-Up Motions for Looms; and I do hereby declare that the following is a full, clear, and exact description thereof, which, in connection with the drawings, making a part of this specification, will enable others skilled in the art to which my invention belongs to make and use the same.

My invention relates to variable take-up motion for looms; and it consists in certain novel features of construction of a variable take-up mechanism to be applied to looms of ordinary construction, and which is operated by the attendant when desired, or automatically without the intervention of the attendant.

The object of my invention is to provide a mechanism by which the speed of rotation of the take-up roll may be varied by the operator or automatically.

Referring to the drawings, Figure 1 is a side view, partly in section, of a portion of a well-known form of loom with my invention applied thereto. Fig. 2 is an end view of some of the parts shown in Fig. 1, looking in the direction of arrow 1, same figure.

My invention relates only to variable take-up mechanism and its mode of attachment and operation upon a loom of any well-known construction and operation. I have, therefore, only shown in the drawings such parts of a well-known form of loom as are essential to the proper understanding of my invention and the operation thereof.

In the accompanying drawings, the part marked *a* is a part of the loom side.

b is a crank secured on the lower shaft of the loom in the usual manner.

d is the push-pawl for operating or turning the take-up roll, which is operated by the crank *b* in the usual manner, said pawl being secured thereto by means of the crank-pin *c*, which is adjustable in a slot in the crank *b*, so as to give the pawl *d* any desired throw.

f is a ratchet-wheel turned by the pawl *d* and secured upon a stud *g*, having its bearing in the loom side or frame *a*. A small pinion, *z*, is also secured upon said stud *g* and turns

with the ratchet-wheel *f*. Said pinion *z* meshes with a gear, *x*, secured upon the end of the cloth-roll *y*.

N is a check-pawl on stud *o*, to hold the ratchet-wheel *f*, and prevent it from turning back when the pawl *d* is raised out of the teeth therein.

The part marked *h* is the shield, which extends over and is supported above the teeth of the ratchet-wheel *f*, as shown in Fig. 1, for the purpose of preventing the end *e* of the pawl *d*, when it is drawn back as the crank *b* revolves, from catching in the ratchet-wheel *f* back of the point of the shield *h* and revolving the ratchet-wheel *f* and the cloth-roll *y* too far by the forward movement of the pawl *d*. If the shield *h* were stationary and always remained in substantially the same position relatively to the teeth of the ratchet-wheel *f* and the end *e* of the pawl *d* when said pawl was moved back out of connection with said ratchet-wheel *f* the take-up motion would always be substantially the same, and it would be necessary for the operator to turn with his hand the ratchet-wheel *f* if he wished for any reason to take up the material faster or to vary the take-up motion, and this has been heretofore generally done; but by my invention this is rendered unnecessary, for the shield *h* is secured to one end of what may be called the "shield-stand" or "support" *i*, which is supported by and movable upon the stud *g*. The other end of said shield-stand *i* is connected with the lower end of the link *k*, which link *k* passes through the guiding piece or stand *l*, attached to the loom side, and is provided with a handle, *p*, at its upper end, by means of which it can be moved up or down through the stand *l*. There is a slot, *m*, in the upper part of the link *k*, into which in this instance the end of the handle *p* enters, being tapped into the piece *n*.

The part marked *q* is an adjusting-piece fastened to the link *k* by the screw *r*, which passes through the slot *m* therein and is tapped into the said piece *q*. When the link *k* is raised to its highest position and the mechanism adjusted to the greatest amount of take-up desired, the adjusting-piece *q* will strike the bottom of the stand *l*, and the spring *s*, secured to the stand *l*, catching under the piece *q*, will hold the link *k* in place.

Below the adjusting-piece *q* an adjusting-

piece or support, *t*, is fastened to the link *k* by the screw *u*, and a spring, *v*, is secured to the piece *t*, as shown in Fig. 1, the upper end of which snaps into the notch *w* in the stand *l* and holds the link *k* in position when the link is raised a certain distance corresponding to a desired amount of take-up.

The mechanism above described is operated by the attendant in the following manner: The several parts of the take-up mechanism being in substantially the position shown in the drawings, if it is desired to vary the take-up motion of the loom and to take up the material faster by reason of the larger west being woven into the material, or for any other reason, the attendant, first having adjusted the piece *t* upon the link *k*, raises the link *k* by the handle *p* until the spring *v* snaps into the notch *w* in the stand *l*; or, if he wishes to raise the link *k* to its highest position, to have the greatest amount of take-up, he adjusts the piece *q* and raises the link *k* until the spring *s* catches under said piece *q*. The raising of the link *k*, fastened to one end of the pivoted or movable support *i*, draws down the other end and also the shield *h* away from the end *e* of the pawl *d*, allowing the end *e* to catch farther back in the ratchet-wheel *f*, according to the distance the shield *h* is drawn back, and to turn the ratchet-wheel *f* a greater distance, as the pawl *d* is moved forward, thus increasing the amount of take-up as may be desired.

Instead of having my variable take-up mechanism operated by the attendant, as above described, it may be operated automatically, if preferred, and I will now proceed to describe the mechanism shown in the drawings for operating it automatically.

The part marked *H* is a part of the drop-box, of the usual and well-known construction, shown in section.

G is the box-chain, which operates the drop-box *H* in the usual and well-known manner.

E is a stand, attached to the loom side *a*, and provided with a stud, *F*, on which the guide-pulley *D* revolves.

B is a hub, movable on the box-chain *G*, and secured thereto at any desired point by the set-screw *C*. A strap, cord, or chain, *A*, is attached at one end to the hub *B*, passed around the grooved pulley *D*, and attached at the other end to the end of the shield stand or support *i*. (See Fig. 1.)

The automatic operation of my variable take-up motion by the mechanism just described is as follows: The hub *B* is properly adjusted upon and secured to the box-chain *G* by the set-screw *C*, so that when the box-chain *G* is moved to its extreme position in the direction of arrow 2, Fig. 1, and consequently the drop-box *H* brought into position to have a certain shuttle thrown from it, (at which time it is desired to have a greater amount of take-up of the cloth,) the end of the arm *i* carrying the shield *h* is pulled down and away from the end *e* of the pawl *d*, allowing

the end of the pawl to drop into the ratchet-wheel *f* farther back, and thus causing it to revolve or turn said ratchet-wheel and the take-up roll a greater distance, in the manner hereinbefore described, as the pawl *d* moves forward. Thus a greater amount of take-up is given to the cloth as long as said lowest compartment of the drop-box is in position. When the lowest compartment of the drop-box *H* is no longer in position to have the shuttle thrown therefrom, the tension on the strap *A* is released, and the spring *M*, secured at one end to the loom-frame and at the other end to the lower end of the link *k* or the end of the supporting-piece *i*, will draw the shield *h* back to its original position, and also the link *k*.

In case it is not desired to operate automatically my variable take-up mechanism, it is only necessary to loosen the set-screw *C* and let the hub *B* be loose upon the box-chain *G*.

If preferred, the variable take-up motion may be operated partly by the attendant and partly automatically, or the mechanism above described for operating it automatically may be left off entirely.

Having described my improvements in variable take-up motions for looms, what I claim as my invention, and desire to secure by Letters Patent, is—

1. The combination, with the ratchet-wheel *f*, the pawl *d*, and the crank for operating the latter, of the movable shield, the shield-support, the link attached to said support, the piece *q*, adjustably secured to said link, the stand *l*, and the spring *s*, substantially as set forth.

2. The combination, with the ratchet-wheel *f*, the pawl *d*, and means for operating the latter, of the shield-support, the link attached to said support, the notched stand *l*, the piece *t*, adjustably secured to said link, and the spring *v*, carried by the said adjusting-piece and adapted to engage the notch in the said stand, substantially as set forth.

3. The combination, with the ratchet-wheel, the pawl, means for operating the latter, the shield, and the movable support for said shield, of the vertically-movable link *k*, the adjusting-pieces *q* and *t*, attached to said link, the springs *s* and *v*, and the stand *l*, substantially as set forth.

4. The combination, with the ratchet-wheel *f*, the pawl *d*, and means for operating the latter, of the movable shield *h*, the shield-support *i*, the spring for moving said support in one direction, the box-chain *G*, and a cord attached to said support and adjustably connected with said box-chain, and thereby adapted to move said support in opposition to the movement imparted thereto by said spring, substantially as set forth.

GEORGE F. HUTCHINS.
